UNITED STATES PATENT OFFICE.

GEORGE W. WEBB, OF ILLION, NEW YORK.

DESIGN FOR A BELT HOOK OR STAPLE.

SPECIFICATION forming part of Design No. 29,405, dated September 27, 1898.

Application filed August 30, 1898. Serial No. 689,873. Term of patent 14 years.

To all whom it may concern:

Be it known that I, GEORGE W. WEBB, a citizen of the United States, and a resident of Ilion, in the county of Herkimer and State of New York, have invented and produced a new and original Design for a Belt Hook or Staple, of which the following is a specification, reference being had to the accompanying drawings, forming a part thereof.

10 Figure 1 shows a side view of the staple of my design. Fig. 2 shows an end or edge view. Fig. 3 shows a plan or top view of the staple as shown in Fig. 1.

15 The feature of the design is the form or configuration of the staple as a whole, and consists of the straight portion between the crooks a a, straight divergent arm portions b b, and the outwardly-inclined point portions c c, having cut points, as shown.

Having described my invention, what I claim as new, and desire to secure by Letters Patent, is—

The design for a belt hook or staple, substantially as herein shown and described.

In witness whereof I have hereunto set my hand, in the presence of two witnesses, this 26th day of August, 1898.

GEO. W. WEBB.
